UNITED STATES PATENT OFFICE.

WILLIAM H. FAULKNER, OF SYRACUSE, NEW YORK.

HURL CUTTING AND SEPARATING MACHINE.

SPECIFICATION forming part of Letters Patent No. 659,441, dated October 9, 1900.

Application filed June 8, 1900. Serial No. 19,610. (No model.)

To all whom it may concern:

Be it known that I, WILLIAM H. FAULKNER, of Syracuse, in the county of Onondaga, in the State of New York, have invented new and useful Improvements in Hurl Cutting and Separating Machines, of which the following, taken in connection with the accompanying drawings, is a full, clear, and exact description.

10 My invention relates to certain improvements in hurl cutting and separating machines, and has for its object a construction whereby the broom-corn may be easily and quickly separated, the short and coarser 15 spears from the long and fine, and also the separating and severing of the heart or central coarse spear from the hurl.

To this end my invention consists in a machine for cutting, separating, and removing 20 the hearts of hurl, having a frame, a suitable knife, wheels and carrier-belts to carry the straw from the said knife, sprocket-wheels and a chain belt thereon having a plurality of pins set in line in each link and adapted 25 to receive the outer loose coarse spears, a separator, a second set of sprocket-wheels and chain belt therefor having pins in each link, between which pins only the fine spears are received, thus separating the heart or coarse 30 central spear in each hurl, a knife supported upon the frame in position to enter between the coarse and fine spears during the movement of the same and to sever and separate the heart from the others, suitable guides, 35 and means for imparting motion to the various movable parts; and my invention further consists in certain other combinations of parts hereinafter described, and specifically set forth in the claims.

40 In the drawings hereto annexed and forming a part of this specification, Figure 1 is a side elevation. Fig. 2 is a top plan view. Fig. 3 is a sectional view taken on line $x-x$ of Fig. 2. Fig. 4 is a vertical transverse sectional view taken on line $y-y$ of Fig. 2. Fig. 5 is an enlarged vertical cross-section taken on line $z-z$ of Fig. 2. Fig. 6 is an enlarged side elevation of a portion of one of the carrier-chains. Fig. 7 is a plan view of the knife 45 for severing the heart from the hurl. Fig. 8 is a perspective view of the separator for sep-

arating the short coarse outer spears from the hurl just after it is cut. Fig. 9 is a vertical cross-section taken just forward of the heart-cutting knife and showing the position and condition of the hurl just prior to the severing operation, and Fig. 10 is a view of a whisk of broom-corn before it is passed through the machine.

55 Referring specifically to the drawings, A is the frame of the machine, provided with bearings for several cross-shafts and receptacles in its lower part to receive the sorted parts of the corn after the same is operated upon and separated. Receptacle A' receives the 60 short coarse outer spears, A'' the coarse inner spears or hearts, and A''' the bunches of fine 65 long spears or the best part of the corn.

A''' is a door forming one end of receptacle A'.

70 B is the driving-shaft, provided with a belt-pulley B' at one end and a sprocket-wheel B'' near the same communicating motion by means of a sprocket-chain C, passing around three other sprocket-wheels C', C'', and C''', of 75 substantially the same size, fixed upon separate shafts D', D'', and D'''.

D is a small wheel mounted on a sliding and slotted adjustable bar E for the purpose of tightening or taking up the slack in the 80 chain C.

85 Mounted on the shaft D''', which is directly above the driving-shaft, are a pair of wheels F F', having grooved peripheries for receiving a pair of carrier-belts F' F', formed, preferably, of leather bands with pins projecting outwardly therefrom and separated widely apart. These belts pass rearwardly or to the left-hand end of the machine, as shown in Fig. 1, around corresponding loose pulleys 90 F'' F'' on shaft D''. Between the pulleys F'' F'' is a sprocket-wheel G', fast on the shaft, which wheel is connected by a chain belt G with a corresponding sprocket-wheel G'', loose on the shaft D''' and between the wheels F F'. 95 The belt G has projecting from each of its sections or links a plurality of pins a , of equal length, arranged in a straight line extending longitudinally of the belt, and serves to receive the fine spears of the hurl between the 100 pins, and thus separate them from the heart or coarse central spear or spears and carry

the hurl with the other carrier-belts upon opposite sides of the same to the receptacle A''' where it is deposited.

H is a wheel with a serrated periphery to one side of the wheel G'' and secured to the shaft to turn therewith and serves to spread the spears and prevent them from entering the spaces between the sections of the chain G. H' is a similar wheel, fast on shaft D', which acts to carry the hearts or coarse central spears forward beneath the heart-cutting knife I, mounted stationary on a support I', secured to the frame A of the machine, as shown in Fig. 7.

J is a rail, angular in cross-section, extending along and secured to the inner side of the frame near the knife I, and this rail serves as a guide for the butt-ends of the whisk and spears and extends just forward of the wheel F toward the end of the machine, where the corn is first operated upon by cutting off the stalk at a point indicated by a broken line w' in Fig. 10.

The knife K is preferably formed of a circular disk and is pivoted to the upper end of a slotted vertically-adjustable bar K', secured to the side of the frame A. Below the knife and fast upon a shaft L, mounted in bearings on the frame, is a wheel K'', formed of a pair of disks provided with hook-shaped projections on its periphery. The disks are separated to receive the edge of the knife K between them and is revolved by means of a chain-belt b, connecting a sprocket-wheel b' on the shaft L with a sprocket-wheel b'' on the driving-shaft. The stalks are one by one fed from the table M into the recesses k between the hook-shaped teeth, and they are carried to the circular knife and cut off.

The driving-shaft D''' is provided with a pair of wheels c c, having grooved peripheries, which wheels are tight on the shaft and connected by carrier-belts c' c' with corresponding wheels c'' c'', loosely mounted on the shaft L. The carrier-belts c' are similar to belts F', above described. Shafts D''' and L are also provided with sprocket-wheels d and d' near the rail J, which are geared together by a chain e, similar to the chain G above referred to, the only difference being that in the chain e the pins are of somewhat smaller diameter, thus providing wider spaces between them to receive the coarse spears. Both of the sprocket-chains e and G are provided with grooves e' in opposite sides to receive the stationary guides f f, which hold the chains perfectly straight on the sides nearest the guide J. The guides f f for the chain G are secured to horizontal brackets f' f'', extending inward from the frame A, as shown in Fig. 5 of the drawings. To the frame A near the cutter K, I arrange a pair of brackets g g, which support, by means of vertically and horizontally adjustable bolts g' g', the notched guide h, which forces the spears in between the pins of the chain e, so that they are carried rearward, and also forces the short outer

coarse spears downward through the separator i, thus removing them from the bunch or bunches of long spears. The separator i is clearly shown in Fig. 8. It consists of straight parallel bars i i'', connected together by cross-bars j at their upper edges. The bar i'' is divided between the cross-bars j to form downward and rearward passages i''' for the short loose spears, and it is through these passages that they are forced during their rearward movement by the notched guide h. The said separator is secured to the inner side of the frame A immediately below the brackets g g.

l is a wire rail secured to the frame A and extending parallel therewith just above and alongside the chain e to hold the hurl down upon the pins of the said chain while the hurl is traveling rearward carried by the belts.

m m indicate horizontal plates of different lengths with inclined sharp front edges to enter between the short and long spears after they are separated by the separator, and m' m' are similar plates to the rear and somewhat above the other plates to pass between the hearts and the fine long spears after the knife I has entered between the same and severed the hearts or coarse central spears from the whisks.

Just forward of the knife I and between the chain G and the guide J is a second and inverted notched guide n, similar to guide h and shown in Figs. 1 and 9, which is suitably supported and vertically adjustable for forcing the spears between the pins in chain G.

p p indicate strips of metal passing around and near the sprocket-wheel d' to serve as guides for the short coarse spears.

q is a clearing device secured to the frame and projecting rearward on opposite sides of the sprocket-wheel G' to insure against the hurl passing upward with the chain and to cause it to fall into the receptacle A'''.

The operation of the machine is as follows: The whisk of broom-corn W (shown in Fig. 10) is first cut on broken line w' to separate the stalk from the hurl. This is affected by laying the whisk horizontally on the table M with the end of its stalk to the left. Then as it is moved toward the knife the hooked projections on the wheel K'' catch it and force it upon the knife, which severs the stalk. After the cutting operation the hurl is carried rearward by the carrier-belts c' c' toward the center of the machine. When the stalk is severed from the hurl, it will be noticed that there are several short outside spears that are quite coarse. These coarse spears are forced downward between the pins a of the chain e by the passing of the hurl beneath the notched guide h, and at the same time and by the same means are forced downward through the inclined passages in the bar i'' of the separator, which separates the butt-ends of the spears, the other ends being separated as the spears move rearwardly by the plates m m. The wire rail l holds the hurl that has not

passed through the separator down upon the ends of the pins *a*, and the whole is passed rearward, the short spears passing below the plates *m* and between the strips *p p*, which 5 guide them downward with the carrier-chains, clear them from the chains, and deposit them in the receptacle *A'*. The hurl containing the heart or central coarse spear continues to pass rearward beneath and by means of the other 10 carrier-belts *F' F'*, and the notched guide *n* by the side of the pins *a* of the belt *G* forces the fine spears between the pins. The heart or coarse central spear or spears, not being able to enter between the pins, are carried below the heart-cutting knife *I*, while the hurl 15 is carried above it. The inclined edge of the knife thus severs the heart from the hurl during the movement of the latter, the heart being deposited in the receptacle *A''* by the 20 wheels *H'*, and the hurl with its fine long spears is carried above the plates *m' m'* to the receptacle *A'''*, where it is deposited, the clearer *q* separating or removing it from the chain *G* and carrier-belts *F' F'*. It will be obvious 25 that many whisks are passing through the machine at the same time and that they are operated upon by the various devices successively.

As the parts of my machine may be changed 30 in form and arrangement without departing from my invention I do not desire to be limited to the precise means shown and described herein.

Having described my invention, what I 35 claim as new, and desire to secure by Letters Patent, is—

1. In a hurl cutting and separating machine, the combination of the frame and the carrier-belts, with means for separating the coarse 40 central spear from the hurl and means for severing the same.

2. In a hurl cutting and separating machine, the combination of the frame, the carrier-belts, a suitable cutter for removing the stalk, 45 with means for separating the short outer spears from the hurl, means for separating the coarse central spear from the hurl and a knife to sever the same therefrom.

3. In a hurl cutting and separating machine, 50 the combination with the frame, of a belt with pins set therein close together, means for forcing the fine spears of the hurl between the pins, a pointed knife to enter between the fine spears between the pins and the coarse spears, 55 and sever the latter from the hurl, and means for imparting motion to the belt, as set forth.

4. In a hurl cutting and separating machine, the combination with the frame, a suitable 60 knife to cut off the stalks, wheels and carrier-belts to carry the straw from the said knife, of sprocket-wheels and a chain belt thereon having a plurality of pins set in line in each link and adapted to receive the outer loose coarse spears, a separator, a second set of 65 sprocket-wheels and a chain therefor having pins in each link between which pins only the fine spears are received, thus separating the

central coarse spear in each hurl, a knife supported upon the frame in position to enter between the coarse and fine spears during their 70 movement, and to sever and separate completely the heart from the hurl, suitable guides, and means for imparting motion to the movable parts, as set forth.

5. In a hurl cutting and separating machine, 75 the combination with the frame, of sprocket-wheels, a chain belt connecting the wheels, and a plurality of pins projecting from each link of the chain, and arranged in a line, and in line with the pins in the other links, said 80 pins having narrow spaces between them to receive the fine spears and reject the coarse spears, as set forth.

6. In a hurl cutting and separating machine, 85 the combination with the frame, of a pair of sprocket-wheels, a chain belt connecting the wheels, pins projecting outward from each link and arranged in a line and in line with the pins of the other links, said links having longitudinal grooves in opposite sides, and 90 straight stationary horizontal guide-bars entering the grooves to hold the chain straight between the sprocket-wheels, as set forth.

7. In a hurl cutting and separating machine, 95 the combination with the frame, table, wheels and suitable carrier-belts to convey the straw in a horizontal position, of sprocket-wheels below the table, a chain belt thereon having pins set in line in each section and in line with the pins in the other sections, a separator, 100 a notched guide, a second set of sprocket-wheels above the table, a chain belt for the latter wheels having pins set in line in each section, a knife supported upon the frame in a horizontal position and in the plane of the 105 movement of the straw, suitable guides and clearers, and means for imparting motion to the sprocket wheels and chains, substantially as described and shown.

8. In a hurl cutting and separating machine, 110 the combination with the frame, table, and suitable means to convey the straw in a horizontal position, of a pair of sprocket-wheels below the table, a chain belt for said wheels having a plurality of pins set in line in each 115 section, a straight separator having inclined passages therein, a notched guide, the separating-plates, a second pair of sprocket-wheels above the table, a chain belt for the latter wheels having pins set in line in each section 120 and closer together than the pins in the other belt, a notched guide for the second chain belt, a knife supported upon the frame in a horizontal position and in the plane of the 125 movement of the straw, suitable guides and clearers, and means for imparting motion to the sprocket wheels and chains, substantially as shown and described.

9. In a hurl cutting and separating machine, 130 the combination with the frame, table, and suitable means to convey the straw in a horizontal position, of a pair of sprocket-wheels below the table, a chain belt for said wheels having a plurality of pins set in line in each

section, a straight separator having inclined passages therein, a notched guide, the separating-plates, a second pair of sprocket-wheels above the table, a chain belt for the latter 5 wheels having pins set in line in each section and closer together than the pins in the other chain belt, stationary horizontal and parallel guide-bars entering grooves in opposite sides of the sections of the chains between the 10 sprocket-wheels, a notched guide for the second chain belt, a knife supported upon the frame in a horizontal position and in the plane of the movement of the straw, suitable guides and clearers, and means for imparting motion 15 to the sprocket wheels and chains, substantially as shown and described.

10. In a hurl cutting and separating ma-

chine, the combination with the frame, of sprocket-wheels and a chain belt connecting the wheels, pins projecting from each link of 20 the chain arranged in line with the pins in the other links, means to hold a portion of the chain passing between the sprocket-wheels straight, said pins having narrow spaces between them to receive only the finer spears, 25 and means to force the fine spears of the hurl between the pins, as set forth.

In testimony whereof I have hereunto signed my name.

WILLIAM H. FAULKNER. [L. S.]
